US0D1002991S

(12) **United States Design Patent** (10) Patent No.: **US D1,002,991 S**
(45) Date of Patent: ** Oct. 31, 2023

(54) **VEGETABLE**

(71) Applicant: **Donaghy Engineering Ltd**, Dungannon (GB)

(72) Inventor: **Stephen Donaghy**, Tyrone (GB)

(**) Term: **15 Years**

(21) Appl. No.: **35/515,008**

(22) Filed: **Jul. 18, 2022**

(80) **Hague Agreement Data**

Int. Filing Date: **Jul. 18, 2022**

Int. Reg. No.: **DM/222767**

Int. Reg. Date: **Jul. 18, 2022**

Int. Reg. Pub. Date: **Aug. 26, 2022**

(30) **Foreign Application Priority Data**

Feb. 8, 2022 (GB) 6190539
Feb. 8, 2022 (GB) 6190540
Feb. 8, 2022 (GB) 6190541

(51) **LOC (14) Cl.** **01-01**

(52) **U.S. Cl.**

USPC **D1/125**; D1/199

Primary Examiner — Katie Jane Stofko

(57) **CLAIM**

The ornamental design for a vegetable, as shown and described.

DESCRIPTION

1. Vegetable
  2. Vegetable
  3. Vegetable
  - 1.1 : Front
  - 1.2 : Back
  - 1.3 : Perspective
  - 1.4 : Perspective
  - 1.5 : Perspective
  - 1.6 : Perspective
  - 1.7 : End view
  - 2.1 : Front
  - 2.2 : Perspective
  - 2.3 : Perspective
  - 2.4 : Perspective
  - 2.5 : Perspective
  - 2.6 : Perspective
  - 2.7 : End view
  - 3.1 : Front
  - 3.2 : Perspective
  - 3.3 : Perspective
  - 3.4 : Perspective
  - 3.5 : Perspective
  - 3.6 : Perspective
  - 3.7 : End view
- 1.1 front view; 1.2 rear view; 1.3 perspective view; 1.4 perspective view; 1.5 perspective view; 1.6 perspective view; 1.7 end view; 2.1 front view; 2.2 perspective view; 2.3 perspective view; 2.4 perspective view; 2.5 perspective view; 2.6 perspective view; 2.7 end view; 3.1 front view; 3.2 perspective view; 3.3 perspective view; 3.4 perspective view; 3.5 perspective view; 3.6 perspective view; 3.7 end view; designs 1, 2 and 3 relate to vegetables cut into decorative shapes.

1 Claim, 21 Drawing Sheets
